ABSTRACT: An emergency cable cutter in which opposed pistons are provided with overlapping cable-cutting blades. The blades have cable-cutting openings therein through which the cable is threaded. Upon the application of pressure to the pistons they are driven toward each other causing the knife edges on the openings to sever the cable. Either of the pistons alone, can sever the cable in the event of failure of the other.

CABLE CUTTER

BACKGROUND OF THE INVENTION

Where hoisting equipment is used in conjunction with helicopters and the like, it is customary to employ steel cables for raising and lowering the loads. In the event of emergency, it becomes necessary to sever the cable with speed and reliability. In multiple cable supported loads, such as four-point support, where failure to jettison all load points simultaneously may result in severe damage, the dependability of cable severing mechanisms becomes most critical.

In order to improve reliability, two independent cutters have been mounted along the cable with the thought that, in the event of partial cable cutter failure, the second cutter would release the load. However, if the cutter located furthest the bell mouth of the hoist, partially cuts the cable, the jammed cable often can support the load and the effectiveness of the second cutter becomes nullified. In such event a catastrophic failure can occur.

In the present invention, a dual configuration cable cutter is provided in which two blades independently operated by opposed piston members cut the cable at the same point, thus eliminating the possibility of the cable jamming in the hoist and causing severe damage.

In the accompanying drawing forming part hereof, there is illustrated one embodiment of the invention, in which drawing identical parts have been given the same reference numeral, and in which:

BRIEF DESCRIPTION OF THE FIGURES

FIG. 1 is a view in longitudinal section of a complete embodiment of the present invention, shown in the prefiring condition.

FIG. 2 is a view similar to FIG. 1 showing the condition of the apparatus following the firing of the cable-severing mechanism.

FIG. 3 is a fragmentary sectional view taken on line 3—3 of FIG. 1 looking in the direction of the arrows.

FIG. 4 is a somewhat isometric view of the piston and cable-cutting portion of the device.

DESCRIPTION OF THE PREFERRED EMBODIMENT

Referring to the drawing and particularly to FIGS. 1 and 2, 10 indicates a cable-cutting device having a substantially cylindrical housing 11 provided with a wall 12 at one end thereof and an internally threaded port 13 at its opposite end. A second internally threaded port 14 is cut into the sidewall 15 of the housing 10 adjacent the end wall 12. The ports 13 and 14 are adapted to receive gas expansion driving means such as pressure cartridges 16 therein.

A pair of opposed piston members 17 are slidably received within the bore 18 of the housing 11. Each of the pistons are provided with sealing rings 19 to prevent the escape of gases between the pistons and the walls of the bore 18 during firing.

The pistons are each provided with flat blades 20 which are cut out of the body of the pistons and which extend in the direction of the center of the housing 11. An arcuate upstanding wall 21 at the cable end of the blades 20 serves as a guide for the blade during firing.

It will be noticed from an examination of FIG. 3, that each

of the blades 20 is provided with an opening 22 therein through which the cable 23 is threaded. The edges of the openings 22 are beveled as indicated at 24 to provide knifelike cable-severing blades. When the emergency cable cutter is as-

sembled, as shown in FIGS. 1 and 2, the pistons and the blades are in opposed relationship with the flats 25 of each of the blades slidably resting upon the flat of the opposed piston blade. Shearpins 26 made of some suitable soft material are slipped through a bore 27 in the housing 11 and into openings 10 28 in the pistons 17. The shearpins prevent the edges of the blades 20 from coming into contact with the cable 23 during normal operation of the hoist.

When it is necessary to sever the cable 23, the pressure cartridges 16 are fired by means of some remote electrical impulse (well known in the art and therefore not illustrated). Expanding gases within the chambers 29, 30 between the ends of the pistons 17 and the pressure cartridges 16 drive the pistons 17 toward each other thereby causing the knives 24 of the blades 20 to sever the cable 23. It will be noted that the cable 20 23 is severed along the plane between the blades 20 and that in the event one of the pistons 17 fails to move by reason of cartridge failure or the like, the opposite piston will perform the necessary blade-severing operation.

The condition of the piston assembly following cable severing will be seen in FIG. 2 in which the shearpins 26 have been cut and the knives 24 brought into position where the opening 22 therebetween has been substantially closed.

From the foregoing it will be seen that there has been provided a highly dependable, compact, fail-safe cable-severing device which is free of the limitations of prior art structures.

Having thus fully described the invention, what is claimed as new and desired to be secured by Letters Patent of the United States, is:

1. A cable-severing device comprising an elongated housing transversely bored to receive the cable therethrough, a longitudinal bore in said housing, opposed pistons, slidably carried within the longitudinal bore, a flat blade member on each of the pistons extending outwardly thereof in the direction of the opposed piston and in overlapping relationship, a cable-receiving aperture in each of the blades, a cable-severing edge on each of the apertures and a pressure cartridge carried by the housing and in communication with each of the pistons to drive the pistons and their blades in the direction of the cable to sever the said cable.

2. A device according to claim 1 in which the ends of the blades opposite the pistons are provided with arcuate upstanding guide portions.

3. A device according to claim 1 in which one end of the longitudinal housing bore is closed by a wall, the opposite end 50 of the bore is closed by the pressure cartridge and a bore is provided in the side of the housing in communication with the longitudinal bore adjacent the end wall to receive a second pressure cartridge.

4. A device according to claim 1 in which the piston blades 55 are prevented from accidental contact with the cable by shearpins carried by the housing and received within radial bores in the said pistons.

5. A device according to claim 1 in which the cutting edges of the blades move along substantially the same plane during the severing action.
